FUSE SETTING MECHANISM FOR GUNS

Bernhardt Jorgensen, Marblehead, Mass., assignor to United Shoe Machinery Corporation, Flemington, N. J., a corporation of New Jersey

Application June 18, 1943, Serial No. 491,353

11 Claims. (Cl. 89—6.5)

1
This invention relates to loading mechanisms for guns, and more particularly to mechanisms for automatically setting the fuse of a shell and immediately thereafter transferring the shell into alignment with the gun and ramming the shell into the gun. The invention is illustrated herein as applied to a gun of large caliber particularly adapted for use in an airplane, although in various aspects it is not thus limited in its applicability.

One object of the present invention is to provide improved fuse-setting mechanism adapted to be placed in operation by endwise movement of the shell into position to be engaged by the fuse-setting mechanism. To this end and in accordance with a feature of the invention, the fuse-setting mechanism comprises a set of knives for gripping the fuse ring of the shell, a set of knives for engaging the body of the shell to hold it against rotation, and means for operating the knives in response to movement of the shell into a predetermined position between the knives.

In accordance with another feature of the invention, means are provided for feeding the shell to the fuse-setting mechanism, the operation of the feeding means being interrupted by the shell in response to its movement into fuse-setting position. The feeding means is in the form of a conveyor chain upon which a plurality of shells are arranged in tandem, and preferably and as illustrated, the chain is driven by fluid-pressure-operated means controlled by an electrically operated valve which is in turn controlled by a normally closed switch opened by the nose of the shell upon its movement into fuse-setting position.

Various features of the invention are to be recognized in the novel organization of means for supporting each shell for the fuse-setting operation and for thereafter transferring each shell into alignment with the gun and for moving it into the breech of the gun. In the illustrated construction, a loading tray is positioned between the feed chain and the fuse setter and fluid-pressure-operated mechanism is provided for moving the tray transversely of the conveyor chain to transfer each shell into alignment with the gun for ramming. Preferably and as shown, the fluid-pressure-operated mechanism is controlled by the fuse-setting mechanism at the completion of the fuse-setting operation, and as each shell is moved into ramming position it is rammed into the breech of the gun by a spring-operated rammer, the operating spring of which

2
is loaded for the next succeeding ramming operation by the gun upon counterrecoil.

As a further feature of the invention, the transfer tray is so mounted that it is automatically moved into alignment with the gun by engagement of the tray with a housing by which the rammer is supported so that regardless of the position in which the gun is aimed the shell will always assume the correct ramming position relatively thereto.

Another feature of the invention relates to members carried by the rammer-supporting housing which support the empty shell case as it is ejected from the gun after firing so that the shell case is properly guided without interference with the loading tray or other mechanism.

These and other features of the invention, including various novel combinations of parts and details of construction, will now be more particularly described by reference to the accompanying drawings and thereafter pointed out in the claims.

In the drawings,
Fig. 1 is a side elevation, partly in section, of one form of apparatus in which the invention is embodied;

Fig. 2 is a plan view, partly in section, of the apparatus shown in Fig. 1;

Fig. 3 is a vertical section through the fuse-setting mechanism;

Fig. 4 is a section on the line IV—IV of Fig. 3;

Fig. 5 is a section on the line V—V of Fig. 3;

Fig. 6 is a side elevation, illustrating the electrical mechanism for operating the valves which control the admission of pressure fluid to the fuse setter for turning it in one direction or the other;

Fig. 7 is a view illustrating progressive positions of the loading tray relatively to the breech end of the gun as a shell is carried from the fuse-setting position into the ramming position;

Fig. 8 is a perspective view of the breech end of the gun, showing a portion of the mechanism by which the rammer is operated; and

Fig. 9 is an electrical diagram of the control system.

As shown in Fig. 1, the shells are supported in end-to-end or tandem relationship by a magazine M. The shells are fed one at a time from the magazine onto a loading tray T which supports the shells during the fuse-setting operation. As the shells are fed onto the tray, the nose of the shell is positioned to be operated upon by a fuse setter F which includes means for holding the shell stationary and for turning the fuse ring of the shell a predetermined amount. After the

fuse has been set, the fuse setter F is moved forward relatively to the shell S which is on the loading tray, whereupon the loading tray is moved upwardly to carry the shell into alignment with a gun G only the breech end of which is illustrated herein. When the shell reaches this position, it is rammed into the gun by a rammer R, and the loading tray and the fuse setter return to the positions illustrated ready to receive another shell from the magazine and to set the fuse thereof.

The magazine M comprises a casing having a top wall 10 and side walls 12 (Figs. 1 and 2) between which walls a plurality of shells are supported in tandem by an endless conveyor chain 14. The casing is carried by legs 16 and 18 extending upwardly from a support 20. The conveyor chain 14, the upper run of which forms the lower wall of the magazine, is carried by a sprocket 22 journaled on a shaft 24 extending between the legs 16 and a second sprocket (not shown) located directly behind a sprocket 26 and carried by a shaft 28 journaled between the side walls 12 at the forward end of the magazine. The shaft 24 carrying the sprocket 22 also forms the means by which the casing 10, 12 is supported by the legs 16. The conveyor chain carries lugs 30 which extend outwardly at spaced intervals and are arranged to engage the rear ends of the shells to carry them forwardly during movement of the conveyor chain.

The conveyor chain is moved at intervals through a distance which is just sufficient to move a shell S onto the loading tray T into the position shown in Fig. 1. This movement of the chain is effected by a rack 32 engaging a pinion 34 journaled on a shaft 36 which is in turn supported by and extends from one of the side walls 12 of the magazine. The pinion 34 is connected by a one-way clutch mechanism 38 (Fig. 2) to a sprocket 40 journaled on the shaft 36 and connected by a sprocket chain 42 to the sprocket 26 fixed to the shaft 28 (Fig. 1). Upon movement of the rack rearwardly, or to the right as viewed in Figs. 1 and 2, it drives the conveyor chain through the clutch mechanism 38 and the sprocket chain 42 to move the shells forwardly. The rear end of the rack 32 is formed as a piston rod 44 to the rearward end of which is secured a piston 46 slidable in a cylinder 48. The piston is normally held in the position illustrated in Fig. 2 by a spring 50 and is arranged to be moved rearwardly by the introduction of fluid under pressure into the cylinder forwardly of the piston upon opening a valve 52. This valve is arranged to be opened automatically by a solenoid 54 at a predetermined time during the operation of the apparatus, as will be later described.

The loading tray T comprises a pair of walls 56 (Fig. 7) arranged in the form of a V between which a shell may be supported. To the under side of the walls 56 are pivotally connected by pins 57 (Fig. 1) a pair of depending brackets 58 which are in turn connected by links 60 and pins 61 to a cross arm 62 of a U-shaped frame having vertical upwardly extending arms 64. These arms are connected at their upper and lower ends to the forward ends of parallel links 66 and 68, respectively, the rearward ends of which are pivoted at 70 and 72 to the spaced arms of a U-shaped supporting frame 74 secured to the support 20. The pins 61 by which the links 60 are connected to the cross arm 62 extend upwardly and are connected by a tension spring 76 which has a connection to the rearward portion of the loading tray T. This spring normally

5 maintains the loading tray in a central position in which it is in alignment with the shells in the magazine M, whereas, the connection of the tray to the crossarm 62 by the links 60 permits swinging movement of the tray in a horizontal plane so that it may be oriented with respect to the gun as the shells are moved into ramming position, as will be explained. It will be noted that the links 60 diverge rearwardly from their connection with the tray so that they do not provide a parallel motion for the tray. Instead, as the tray is swung on the arms in accordance with the position of the gun in azimuth, the links, by reason of their non-parallel relationship, cause 10 the tray also to turn as it is swung laterally, and the arrangement of the links is such that when the forward portion of the tray is moved into a position adjacent to the breech end of the gun, the tray will be in axial alignment with the gun, regardless of the position of the gun. The 15 spring also supports the rearward end of the tray but permits rocking movement of the tray in a vertical plane about the pivotal connections to the brackets 58 so that the loading tray may 20 assume the same position in elevation as the gun when the shells are moved into ramming position. The brackets 58 have forwardly extending abutments 78 between which are positioned compression springs 83. 25 These springs cooperate with the spring 76 normally to maintain the tray in a horizontal position but permit some depression of the forward end of the tray to align the shell with the gun if the gun is pointed slightly downward.

30 The links 66 have rearwardly and downwardly extending arms 78 which have pin-and-slot connections 80 with pistons 82 movable in cylinders 84. Upon introduction of pressure fluid into the cylinders rearwardly of the pistons, the pistons 40 are moved forwardly and, by reason of their connections to the arms 78 of the links 66, cause the loading tray T, with the shell carried thereby, to be elevated. The cylinders 84 are connected by pipes 86 and a pipe 88 to a valve 90 by which 45 the flow of pressure fluid into the cylinders is controlled. This valve is operated by a solenoid 92 which, when energized, opens the valve and permits flow of pressure fluid into the cylinder and, upon de-energization closes the valve and disconnects the cylinders from a source of pressure fluid. Pressure fluid within the cylinders is exhausted through a pipe 94 and upon closure of the valve 90 the loading tray returns by gravity to the position shown in Fig. 1.

55 In order that the loading tray will be properly oriented with respect to the gun as the tray carries a shell S into ramming position, a pair of spaced rolls 94 is carried by each of the walls 56 of the loading tray. These rolls are journaled 60 in brackets 96 secured to the upper outer surfaces of the walls at each end of the tray. The rolls are arranged to engage walls of a rammer housing 98 extending rearwardly from the breech end of the gun and secured thereto by a bracket 100. This housing, as shown in Fig. 7, comprises spaced walls 102 the upper portions of which are parallel and the lower portions of which are divergent. The divergent portions of the walls carry plates 104 having hinge portions 106 extending through apertures in the walls and pivoted to the outer surfaces thereof. Arms 108, rigidly connected to the plates 104, cooperate with the outer surfaces of the walls to prevent downward movement of 65 the plates beyond the horizontal positions illus-

trated. As the loading tray carrying the shell is moved upwardly, the plates 104 are moved upwardly into engagement with the inner surfaces of the walls 102, as shown in Fig. 7, and the rolls 96 on the loading tray engage these walls. By reason of the mounting of the loading tray for movement in both horizontal and vertical planes, it will be swung by the engagement of the rolls with the plates 104 as the tray is moved upwardly so that the shell carried therewith is in alignment with the gun barrel regardless of the position of the gun. After the shell has been rammed, in a manner to be explained, the plates assume the horizontal positions shown at the left in Fig. 7 and serve to guide the shell case as it is ejected from the gun following the firing.

The rammer R, by which the shell is rammed into the gun after it is in the proper position, comprises a sprocket chain 110 (Figs. 1 and 2) carried by sprockets 112 and 114. The sprocket 112 is journaled in a bracket 115 supported on the breech block (not shown) for vertical movement therewith, and the sprocket 114 is carried by a shaft 118 supported between the upper rearward portions of the walls 102 of the housing 98. The chain 110 carries lugs 116 arranged to engage the rear end of the shell and force it into the breech of the gun as the chain is driven. For driving the chain, the shaft 118, carrying the sprocket 114, has mounted on its outer end a sprocket 120, connected by a drive chain 122 to a sprocket 124 (Figs. 2 and 8) mounted on a shaft 126 journaled in a bracket 128 secured to the breech end of the gun, and in the adjacent wall of the breech. The shaft 126 carries a pinion 130 connected thereto by a suitable one-way clutch mechanism, and this pinion is arranged to be rotated by a rack 132 extending forwardly and connected at its forward end to a rod 134 (Fig. 2) passing through a cylinder 136 mounted in a bracket 137 coaxial with the horizontal trunnions of the gun. The rod 134 carries a collar 138 which engages one end of a compression spring 140, the forward end of which engages a forward wall of the cylinder 136. This spring urges the rod and the rack 132 rearwardly, but these members are normally constrained against such movement by a latch 144 pivoted to the gun and having a portion which engages the rear end of the rack, as shown in Fig. 8. Upon pivoting the latch upwardly, the rack is free to be moved rearwardly by the spring 140 to drive the rammer chain 110 through sprocket 124, drive chain 122 and sprocket 120. For releasing the latch when it is time to ram a shell, a release arm 146, connected at one end to the latch, has its other end extending through a hole in one of the walls 102 of the rammer housing, as shown in Fig. 7, in position to be engaged by a shell S. When a shell has been moved into ramming position, as shown at the right in Fig. 7, the shell engages the end of the arm 146, moving it upwardly a sufficient distance to release the latch 144, whereupon the rack 132 is actuated by the spring 140 to drive the rammer chain 110 and to drive the shell into the breech of the gun. After the shell has been thus introduced into the gun, the breech block is closed in any conventional manner and the gun is fired. The breech block moves upwardly in its closing movement lifting the bracket 115 which supports the forward end of the rammer chain 110 so that the chain is pivoted about the axis of the rear supporting shaft 118. During the recoil of the gun the latch 144 moves rearwardly with it until it is hooked over the end of the rack

132 which is at this time rearwardly of the position shown in Figs. 2 and 8, the spring 140 being fully expanded. Upon counterrecoil, as the gun returns to battery, the latch moves the rack back to the position shown in Fig. 2, at the same time compressing the spring 140 so that the spring is loaded in readiness for the next ramming operation. It will be understood that during the recoil of the gun, the pinion 130 (Fig. 8) movable with the gun, moves relatively to the rack and is therefore rotated in a direction opposite to that in which it was rotated during the ramming operation. However, no motion is transmitted during recoil to the sprocket 124 through the one-way clutch mechanism.

Prior to the upward movement of the loading tray T from the position shown in Fig. 1 into ramming position, the fuse of the shell is set by mechanism which will now be described. The fuse setter F, as shown in Figs. 3 and 5, includes a base 150 secured to the support 20. The upper portion of the base is channelled to provide guideways 151 in which is supported a carriage 152 for limited sliding movement lengthwise of the magazine. The carriage is normally maintained in the position shown in Figs. 1 and 3 by a pair of tension springs 154 secured between pins 155 extending outwardly from the carriage 152 and pins 157 extending upwardly from the base 150. A plate 156, secured to the rearward wall of the base and projecting thereabove, limits the rearward movement of the carriage by the springs 150; whereas forward movement of the carriage is limited by a similar plate 158 secured to the forward wall of the base. The carriage is arranged to be moved forwardly against the force of the springs 154 after the fuse has been set so that the shell may be moved vertically without any interference from the fuse setter. For this purpose, a fluid-pressure motor comprising a piston 160, movable in a cylindrical bore 162 in the base 150, is provided. The forward end of the piston 160 engages a depending portion 164 of the carriage so that upon the introduction of pressure fluid behind the piston, the carriage is moved forwardly until it is in engagement with the plate 158. The flow of pressure fluid into the space behind the piston is controlled by a valve 166 (Fig. 5) operated by a solenoid 168, so that upon energization of the solenoid the valve operates to permit pressure fluid to flow from a high-pressure line 170 into the space behind the piston. Upon de-energization of this solenoid the valve is moved by a spring 172 into closed position in which it permits the exhaust of fluid behind the piston 160 through a pipe 174, whereupon the carriage 152 is moved back to the position shown in Figs. 1 and 3 by the springs 154.

The fuse-setting instrumentalities include a set of knives 176 arranged to be moved into engagement with a fuse ring 178 of the shell S and other knives 180 and 182 (Fig. 4) arranged to grip and hold the shell rearwardly of the fuse ring during the fuse-setting operation. The knives 176 are carried by a cage 184 which is rotatably mounted in an upwardly projecting portion 186 of the carriage 152. These knives are formed at the rearward ends of levers 188 fulcrumed on pins 190 in the cage 184. The forward ends of the levers are connected by toggle links 192 and 194 to a hollow rod 196 slidable in the forward end of the cage 184. This end of the cage is formed as a sleeve 198 which passes through the portion 186 of the carriage and has secured to its mid-portion a pinion 200. A bush-

ing 202 surrounds a sleeve 203 formed on the pinion 200 and the sleeve 198 and cage 184 are held against axial movement by a nut 204 threaded on a reduced forward portion of the sleeve. A bushing 206 is secured to the forward portion of the hollow rod 196 and is slidable within the adjacent portion of the sleeve 193. This rod is normally urged forwardly of the carriage 152 by a compression spring 208 acting between the bushing 206 and the cage 184 so that the knives 176 are normally maintained out of engagement with the fuse ring 178 of the shell.

The knives 180, arranged to engage the shell rearwardly of the fuse ring, are stationarily supported in a bracket 210 (Fig. 4) secured by screws 212 to the rearward end of the carriage 152. The knife 182 is mounted for vertical movement in the bracket 210 and upon being moved upwardly the shell is gripped between the stationary knives 180 and the movable knife 182 against rotative movement, so that with the knives 176 in engagement with the fuse ring the fuse may be set by turning the cage 184.

For thus moving the knives 176 and the knife 182, a fluid-pressure motor, composed of pistons 214 and 216 movable in a cylinder 218 formed in the carriage 152, is provided. The cylinder 218 has an inlet port 219 located between the pistons 214 and 216 so that upon the introduction of pressure fluid into the cylinder the pistons move outwardly in opposite directions. The piston 214 acts upon the lower end of a lever 220 pivoted at 222 on a bracket 224 extending forwardly from the carriage 152. The upper end of the lever 220 is forked and carries rolls 226 received in an annular groove in the bushing 206 on the forward end of the hollow rod 196. The other piston 216 acts upon an arm 228 of a bell-crank lever pivoted at 230 within a recess formed in the rearward side of the carriage 152. The other arm 232 of the bell-crank lever carries a roll 234 engageable with the lower end of the slideable knife 182. The bell-crank lever is normally urged in a clockwise direction by a spring 236 so that when no pressure is exerted between the pistons the bell-crank lever moves the piston 216 inwardly permitting the knife 182 to drop by gravity out of engagement with the shell. The spring 208, acting on the rod 196, maintains this rod in a forward position when there is no pressure between the pistons, and accordingly the adjacent ends of the pistons are located in proximity to each other. The adjacent portions of the pistons carry packing members 240 secured to the pistons by screws 242. The heads of these screws extend outwardly beyond the packing members and accordingly prevent actual contact of the adjacent ends of the pistons so that the inlet port 219 is never closed thereby.

Upon the introduction of pressure fluid between the pistons they are moved outwardly into the positions shown in Fig. 3 so that the knife 182 cooperates with the stationary knives 180 to hold the shell against rotation. The hollow rod 196 is moved rearwardly or to the right, thus moving the toggle links 192, 194 toward straightened conditions so that the knives 176 are moved into gripping relationship with the fuse ring 178. The flow of pressure fluid into the cylinder 218 between the piston 214 and 216 is controlled by a valve 244 (Fig. 5) which is moved to open position upon energization of a solenoid 246. Accordingly, upon energization of this solenoid, the fuse-setting knives 176 are moved into engage-

ment with the fuse ring 178 of the shell and the shell is locked against bodily rotation by the knives 180 and 182. Upon de-energization of the solenoid the valve 244 cuts off the flow of pressure fluid into the cylinder 218 and opens the cylinder to an exhaust 248, whereupon the fuse-setting knives are immediately moved out of engagement with the fuse ring by the spring 208 and the bell-crank lever is moved by the spring 236 to permit the knife 182 to drop away from the shell so that the shell is no longer held by the knives 180 and 182.

For turning the cage 184 by which the fuse-setting knives 176 are supported thereby to set the fuse, a fluid-pressure motor comprising a piston 250 (Fig. 5) slidable in a cylinder 252, formed in a lateral extension 254 of the carriage 152, is provided. Formed integrally with the piston 250 is a rack 256 engageable with the lower side of the pinion 200 mounted on the sleeve 198 of the cage 184. Upon the introduction of pressure fluid into the cylinder 252 rearwardly of the piston 250 the piston is moved to the left as viewed in Fig. 5 and imparts rotative movement to the cage 184 to set the fuse. For returning the cage 184 to its initial position after the completion of the fuse-setting operation, a rack 258 is provided engageable with the pinion 200 opposite the rack 256. The rack 258 is integral with a piston 260 movable in a cylinder 262 formed in the extension 254 of the carriage 152. During the fuse-setting operation the piston 260 will be moved to the right by the pinion 200 and in order to return the fuse setter to its initial position, pressure fluid is introduced into the cylinder 262 rearwardly of the piston 260 to move this piston to the left, whereupon the piston 250 is returned to the position shown, the pressure fluid within the cylinder 252 being permitted to exhaust during this movement.

For controlling the admission of pressure fluid into the cylinders 252 and 262 a valve mechanism 264 is provided. This valve mechanism includes a casing having a high pressure chamber 266 in constant communication with a pressure line 268 and a low pressure or discharge chamber 270 from which fluid discharges through a pipe 272. The valve mechanism 264 also includes a pair of sleeve valves 274 and 276 connected by a lever 278 for equal and opposite movements in response to movement of the lever about its supporting pivot 279. With the sleeve valve 274 in the position illustrated in Fig. 5, communication between a set of ports 280 and 281 in a pipe 282 is cut off by a partition 284 in the pipe and any fluid within the cylinder 252 may pass through the ports 280 to the discharge pipe 272. At this time, however, similar ports in a pipe 286 associated with the cylinder 262 are in communication by way of the sleeve 276 so that the cylinder 262 is connected to the pressure chamber 266, whereas the sleeve 276 prevents discharge of the fluid within the cylinder 262 so that the pistons 250 and 260 are normally maintained in the positions illustrated in which the fuse setter is in a zero position. Upon movement of the lever 278 in a clockwise direction to reverse the positions of the sleeve valves 274 and 276, it will be understood that pressure fluid is admitted to the cylinder 252 and discharges from the cylinder 262 so that the piston 250 is moved toward the left to impart a fuse-setting movement to the cage 184. The lever 278 is operated by a pair of solenoids 290 and 292 the armatures of which are connected to an arm 294 keyed to the shaft 279 by which

the lever 278 is carried. Upon energization of the solenoid 292, the arm 294 is moved upwardly to rock the lever 278 in a clockwise direction to re-reverse the positions of the valves. This operation is effected upon only a momentary energization of the solenoid as the valves will remain in the positions to which they are moved until the other solenoid is energized. The solenoid 290 will be energized after the fuse-setting operation has been completed to move the valve back to the positions illustrated, whereupon the cage 184 supporting the fuse-setting knives will return to its initial position, as will be explained herein-after.

For controlling the fuse-setting time, a switch 300 is adjustably mounted by means of a screw 302 on a slideway formed in a bracket 304 secured to and extending laterally from the carriage 152. This switch includes a pivoted actuating arm 306 having an upwardly extending projection 308 in the path of movement of the rack 256 so that after the fuse ring has been turned a predetermined amount, depending upon the position of the switch 300 on the bracket 304, the switch arm 306 will be rocked in a counter-clockwise direction against the tension of a spring 310. As will be explained in detail as the description proceeds, this movement of the switch arm opens a circuit to the solenoid 246, whereupon the valve 244 closes and permits exhaust of pressure fluid from between the pistons 214 and 216 (Fig. 3) so that the fuse-setting knives move out of engagement with the shell and the fuse-setting operation stops. Any suitable mechanism may be employed for operating the screw 302 to position the switch 300 in accordance with the desired fuse-setting and, as illustrated herein, the screw is connected by a flexible shaft 312 and bevel gearing 314, 316 to an actuating handle 318. A pointer 320 carried by the gear 316 cooperates with a suitably calibrated scale so that after the desired fuse-setting time has been determined, the handle 318 is turned until the pointer registers with the number of fuse seconds desired and the switch 300 is positioned accordingly.

The various circuits by which the different operations are controlled to obtain the proper sequence of operations will now be described in detail with reference to Fig. 9. The energization of the solenoid 54, by which the operation of the shell-feeding chain 14 is controlled, is in turn controlled by three different switches which insure that the loading tray is in its proper position, that the fuse-setting mechanism is in its proper position and that a shell is not already positioned with its nose in the fuse setter, when the chain is operated. Carried by one of the vertical arms of the U-shaped bracket 74 which support the tray-elevating links is a switch 324 arranged to be closed by one of the links 66 when the loading tray is in its lower or shell-receiving position. As shown in Fig. 9, the switch 324 includes a pair of spaced contacts 326 and 328 arranged to be connected by a switch arm 330 when the links 66 are in the positions illustrated in Fig. 1, at which time the loading tray is in its lowermost position. As soon as the loading tray has been elevated from this position, however, the switch arm 330 is moved out of engagement with the contacts 326 and 328 by a spring 332. Connected in series with the switch 330 is a switch 334 carried by the plate 156 (Fig. 3) forming the stop for the rearward movement of the carriage 152. This switch includes a pair of spaced contacts 336, 338 and a switch arm 340 (Fig. 9) ar-

ranged to connect the contacts when the switch is in the position shown in Fig. 9. This switch is operated by the carriage 152 when in its rearward or fuse-setting position by its engagement with a pin 342 connected to the switch arm 340 and extending through the plate 156 in the path of movement of the carriage. Accordingly the switch 334 is closed only when the fuse setter is in its rearward or fuse-setting position. A third switch 344 is in series with the switches 324 and 334. This switch is secured to a bracket 346 extending forwardly from the carriage 152 and includes a pair of spaced contacts 348 and 350 arranged to be closed by a switch arm 352 when there is no shell in the fuse setter. The switch arm is normally held in position to connect the contacts 348 and 350 by a spring 354 and is arranged to be moved against the force exerted by the spring by a rod 356 (Fig. 3) extending through the hollow rod 196 and terminating in a portion arranged to be engaged by the nose of a shell S when the shell has been moved into the proper fuse-setting position. Accordingly, it will be understood that when no shell is in the fuse setter the contacts 348 and 350 are connected by the switch arm 352. With the switches 324, 334 and 344 closed, the solenoid 54 is energized by the following circuit: from line wire 360 through wire 362, switch 324, wire 364, switch 334, wire 366, contacts 348 and 350 of switch 344, wire 368 to the solenoid, and back through wire 370 to a line wire 372. Thus with the loading tray in its shell-receiving position and the fuse setter in its rearward position the solenoid 54 is energized to open the valve 52, whereupon the conveyor chain 14 is operated by the fluid-pressure motor, comprising piston 46 and cylinder 48, to feed a shell onto the loading tray T. After a shell has been fed onto the loading tray into the position shown in Figs. 1 and 3, the switch arm 352 is moved out of engagement with the contacts 348 and 350 of the switch 344 to break the circuit to the solenoid 54, whereupon the feeding movement stops.

After the shell has been thus fed into fuse-setting position, the fuse-setting knives are automatically moved into engagement with the shell as follows: The switch 344 operated by the shell includes a second pair of contacts 374 and 376 which are normally open but are closed by movement of the switch arm 352 by the shell at the end of the feeding operation. A circuit is now completed to the solenoid 246 which operates the valve 244 to admit pressure fluid between the pistons 214 and 216 which operate the fuse-setting knives. This circuit is as follows: from the line wire 360 through wire 380, contacts 374 and 376 of switch 344, wire 382 through the solenoid 246, wire 384, contacts 386, 388 of the switch 300 which are normally closed by a switch arm 390, and back through wire 392 to line wire 372. Thus after the shell has been moved into fuse-setting position, the fuse-setting knives are automatically moved into engagement therewith and the mechanism then comes to rest with the shell ready for the fuse-setting operation, this being the position of the parts with the mechanism at rest at the end of the cycle of operations.

The cycle of operations is started by pressing a manually operated push button 394 after the desired fuse-setting time has been determined and the switch 300 has been positioned accordingly. Depression of the push button 394 connects switch contacts 396 and 398 to complete a circuit through the solenoid 292 as follows: from line

wire 360 through wire 400, contacts 396, 398, wire 402, solenoid 292 and wire 424, back to the line wire 372. Energization of this solenoid operates the valve 274 (Fig. 5) to admit pressure fluid to the cylinder 252, whereupon the piston 250 and rack 256 are moved to the left to impart rotative movement to the cage 184 to turn the fuse ring 176 of the shell S. When the fuse ring has been turned an amount corresponding to the previous setting or positioning of the switch 300, the arm 308 is rocked in a counterclockwise direction to break the circuit through the solenoid 246 at the contacts 386 and 388 (Fig. 9). Immediately the fuse-setter knives are moved out of engagement with the fuse ring 178 and the fuse-setting operation stops.

The movement of the arm 308 by the rack 256, after the fuse has been set to the desired value, also causes a circuit to be completed through a pair of contacts 410 and 412 of the switch 300 to energize the solenoid 168 as follows: from the line wire 360 through wire 414, contacts 410 and 412, wire 416, solenoid 168 and wire 418, to the line wire 372. The energization of this solenoid opens the valve 166 to admit fluid pressure into the cylinder 162 behind the piston 160, causing the fuse-setter carriage 152 to be retracted or moved to the left as viewed in Fig. 3, thereby to free the shell for its transfer into ramming position. This transfer does not occur until the fuse setter has been fully retracted, at which time it operates a switch 420 secured to the plate 158 which limits the movement of the fuse-setter carriage by the piston 160.

After the fuse-setter has been fully retracted, a circuit through the solenoid 92, which operates the valve 90 to admit pressure fluid into the transfer-tray-lifting cylinders 84, is completed as follows: from the line wire 360 through wires 400, 422, contacts 424, 426 of the switch 420, wire 428, arm 430 of a switch 432, wire 434, solenoid 92 and wire 436, to the line wire 372. The switch 432 may be mounted on the breech end of the gun, as indicated in Fig. 8, and is arranged to be actuated by a projection 440 of the rack 132 which operates the ramming mechanism. When the rack is in the position shown with the spring 140 (Fig. 2) loaded, the switch arm 430 is in engagement with a contact 442. Upon movement of the rack rearwardly of the gun to ram the shell, the switch arm 430 is moved into engagement with a second contact 444 and upon movement of the gun in counter-recoil to return the rack 132 to the position illustrated, the switch arm is moved back into engagement with the contact 442. The switch arm is pivoted on a pin 446 (Fig. 9) and a tension spring 448 connected to the switch arm provides a snap action therefor.

With the fuse setter in its fully retracted position and the solenoid 92 energized, the loading tray is elevated to carry the shell into ramming position in alignment with the gun. The loading tray is self-aligning, as has been explained, so that the shell is carried into the proper position regardless of how the gun is aimed. After the shell has thus been moved into ramming position, the arm 146, connected to the latch 144 which maintains the rack 132 of the rammer-operating mechanism in the position shown in Fig. 8, is engaged by the shell to release the latch. The rack 132 is thus released to the action of the spring 140 to operate the rammer R and load the shell in the gun. Any suitable means, not illustrated, may be provided for automatically

closing the breech block after the shell has been properly rammed and for firing the gun.

During the early part of the ramming movement, the rack 132 moves the switch arm 430 away from the contact 442 and into engagement with the contact 444. This interrupts the circuit through the solenoid 92 so that the loading tray returns to its lower position in alignment with the shells in the magazine in readiness to receive another shell during the next feeding movement. This movement of the loading tray closes the switch 324, and it will be understood that the contacts 348 and 350 of the switch 344 are closed, inasmuch as no shell is in the transfer tray. However, the feeding does not begin until the fuse-setter carriage 152 has returned to its normal position to close the switch 334. The engagement of the arm 430 of switch 432 with the contact 444 closes a circuit through the solenoid 290 of the fuse setter as follows: from the line wire 360 through wires 400, 422, switch 420 which is still closed, wire 428, switch arm 430, contact 444, wire 450, solenoid 290 and wire 452, to the line wire 372. The energization of the solenoid 290 swings the lever 278 of the valve 264 back into the position illustrated in Figs. 5 and 6, whereupon fluid under pressure flows into the cylinder 262 and exhausts from the cylinder 252 to return the racks to the positions illustrated and to return the fuse setter to its initial or zero position. At the beginning of this movement of the rack 256 the arm 308 of the switch 309 is returned by the spring 310 to the position shown in Figs. 5 and 9, thus opening the circuit through the solenoid 168, whereupon the valve 166 closes and the fuse-setter is moved back to its operative position by the springs 154. After the fuse setter has returned to its operative position the switch 334 is closed, whereupon the solenoid 54 of the shell-feeding mechanism is energized, as heretofore explained, to feed another shell onto the loading tray. This feeding movement continues until contacts 348 and 350 of the shell-operated switch 344 are opened, at which time the contacts 374 and 376 of this switch are closed. The closing of these contacts energizes the solenoid 246 to admit fluid under pressure into the cylinder 218 whereupon the fuse-setting knives are moved into engagement with the shell. The apparatus then comes to rest with the shell in position for a fuse-setting operation, and after the switch 300 is properly positioned by the controller 318 and the manually operated switch 394 closed, the foregoing cycle of operations is repeated.

After ramming of the shell, the plates 104 associated with the rammer mechanism return to their horizontal positions, as shown at the left in Fig. 7, so that after firing of the gun the ejected shell will be supported in its rearward movement by these plates so that it will be thrown clear of the fuse-setting mechanism and a suitable receptacle may be provided if desired for receiving the ejected shells.

It will thus be seen that a fully automatic feeding, fuse-setting and loading mechanism has been provided which goes through an entire cycle of operations upon the closing of a manual switch to set the fuse, transfer the shell into ramming position, ram the shell, feed another shell into fuse-setting position and grip the nose of the shell in readiness for a subsequent fuse-setting operation, these operations taking place in the order named. The various operations, with the exception of the ramming, are effected by fluid-

pressure mechanisms and the ramming is effected by a spring loaded during counterrecoil of the gun. There is thus provided a fully automatic mechanism suitable for setting the fuses of shells and loading the shells, adapted for use with guns of large caliber.

The construction of the rammer and the means for alining the shell with the bore of the gun preparatory to the ramming operation are not claimed herein, but form the subject matter of divisional application Serial No. 569,540, filed December 23, 1944, now Patent No. 2,425,425, granted August 12, 1947, in my name.

Having thus described the invention, what I claim as new and desire to secure by Letters Patent of the United States is:

1. In combination, fuse-setting mechanism comprising a set of knives for gripping the fuse-adjusting member of a shell, means engageable with another portion of the shell for holding the shell against movement during the fuse-setting operation, fluid-pressure-operated means for moving said knives into engagement with the fuse-adjusting member of the shell and for operating said holding means to prevent movement of the shell, fluid-pressure-operated means for feeding a shell into a position in which the nose of the shell lies between said knives, and means operative in response to movement of a shell into said position for admitting pressure fluid to the first-named fluid-pressure-operated means and for shutting off the supply of pressure fluid to the last-named fluid-pressure-operated means.

2. In combination, fuse-setting mechanism including a plurality of knives engageable with the fuse-adjusting member of a shell, means for feeding a shell into a position in which the nose of the shell lies between said knives, and means operative in response to movement of the shell into said position for interrupting the operation of the feeding means and for moving the knives into engagement with the fuse-adjusting mechanism of the shell.

3. In combination, fuse-setting mechanism including a plurality of knives engageable with the fuse-adjusting member of a shell, means for feeding a shell into a position in which the nose of the shell lies between said knives, fluid-pressure-operated means for moving said knives into engagement with the fuse-adjusting member of the shell, fluid-pressure-operated means for operating said feeding means, and means operated by the nose of a shell in response to movement of the shell into said position for admitting pressure fluid to the first fluid-pressure-operated means and for interrupting the flow of pressure fluid to the second fluid-pressure-operated means.

4. In combination, means for feeding shells in tandem fuse-setting means positioned to receive the nose of the leading shell and arranged to set the fuse of the shell while the shell is held motionless, said fuse-setting means including means arranged to be engaged by the nose of the leading shell for interrupting the operation of the feeding means.

5. In combination, an endless conveyor for supporting and feeding shells in tandem, fuse-setting means positioned to receive the nose of the leading shell and arranged to set the fuse of the shell while the shell is held motionless, fluid-pressure-operated means for operating said conveyor, and means engageable by the nose of the shell for interrupting the flow of pressure fluid to said fluid-pressure-operated means in response

to movement of the shell by the conveyor into a predetermined position with respect to said fuse-setting means.

6. In combination, means for feeding shells in tandem, fuse-setting means positioned to receive the nose of the leading shell, means for operating said fuse-setting means to set the fuse of the shell after it has been moved by said feeding means into fuse-setting position, and means operative in response to operation of the fuse-setting means to set the fuse a predetermined amount for retracting the fuse-setting means and moving the shell transversely to the direction of feed into position to be rammed into a gun.

15 7. Gun-loading mechanism comprising a loading tray movable transversely of the breech end of a gun for carrying a shell into ramming position, means for feeding a shell onto said loading tray, and a fuse setter positioned to receive the nose of a shell on the loading tray, said fuse setter including means for interrupting the operation of said feeding means after the shell has been moved into a position in which the nose of the shell is correctly positioned for the fuse-setting operation.

8. Gun-loading mechanism comprising a loading tray movable transversely of the breech end of a gun for carrying a shell into ramming position, means for feeding a shell onto said loading tray, fuse-setting means positioned to receive the nose of the shell on the tray, said fuse-setting means including means operative in response to movement of the shell into a predetermined position on said tray for operating the fuse-setting means and interrupting the operation of the feeding means, and means operative in response to the setting of the fuse a predetermined amount for moving said loading tray to carry the shell into ramming position.

40 9. In combination, a gun, means separate from the gun for supporting a plurality of shells in end-to-end relation, means for moving said supporting means to move the shells one at a time into fuse-setting position, means for setting the fuse of each shell after it has been thus moved, and means operative in response to a completion of the fuse-setting operation for transferring the shells from the fuse-setting position into position to be rammed into the gun.

45 10. In combination, a gun, an endless conveyor chain mounted separately from the gun for supporting a plurality of shells in end-to-end relation, means for operating said chain to move the shells one at a time into fuse-setting position, means for setting the fuse of each shell after it has been thus moved, and means operative in response to a completion of the fuse-setting operation for transferring the shells from the fuse-setting position into ramming position.

50 11. In combination, a gun, means separate from the gun for supporting a plurality of shells in tandem, means for moving said supporting means to carry the shells one at a time into fuse-setting position, a transfer tray on which the shells are supported in fuse-setting position, means for setting the fuse of each shell while on the transfer tray, and means operative in response to a completion of the fuse-setting operation for moving said tray to carry the shells from fuse-setting position into ramming position.

BERNHARDT JORGENSEN.
